(57) **CLAIM**

The ornamental design for a craft punch, as shown and described.

DESCRIPTION

FIG. 1 is a front view of a craft punch;

FIG. 2 is a rear view thereof;

FIG. 3 is a right-side view thereof;

FIG. 4 is a left-side view thereof;

FIG. 5 is a top view thereof;

FIG. 6 is a bottom view thereof;

FIG. 7 is a front perspective view thereof;

FIG. 8 is a rear perspective view thereof; and,

FIG. 9 is another front perspective view thereof showing the positioning members rotated in an alternative position.

The broken lines depict environmental subject matter only and form no part of the claimed design.
